UNITED STATES PATENT OFFICE.

CHARLES W. ISBELL, OF NEW YORK, N. Y.

HYDRAULIC MAIN FOR GAS-WORKS.

SPECIFICATION forming part of Letters Patent No. 311,585, dated February 3, 1885.

Application filed January 29, 1884. (No model.)

To all whom it may concern:

Be it known that I, CHARLES W. ISBELL, of the city and county of New York, in the State of New York, have invented a new and 5 useful Improvement in Hydraulic Mains for Gas-Works, of which the following is a specification.

In gas-works as commonly constructed the hydraulic main is arranged transversely to and 10 above the bench of retorts, and from the mouth-piece of each retort a stand-pipe extends upward, and is connected by a bridge-pipe with the dip-pipe, which extends downward into the hydraulic main and below the liquid-level 15 therein.

My invention relates to that class of hydraulic mains which are provided opposite the several dip-pipes with a corresponding 20 number of lateral casings or branches separate from and independent of each other, communicating with the interior of the main below the liquid-level therein, and having their outlets or mouths presented on the exterior of the main above the liquid-level therein, and provided with separately-removable 25 lids or covers. The tar and other matter which accumulates below each dip-pipe can be then withdrawn from the main by separately removing the lids or covers of the casings or 30 lateral branches, and while the works are in operation.

The invention consists in a hydraulic main having a number of dip-pipes extending vertically downward into it, provided in its bottom with depressions or pockets directly below the downwardly-presented ends of the vertical dip-pipes, and having lateral branches or cleaning-holes extending from the depressions or pockets to the exterior of the main 35 above the liquid-level, and there provided with separately-removable lids or covers. The depressions or pockets in the bottom of the main itself form receptacles into which the tar falls from the dip-pipes, and prevent the tar 40 above the liquid-level, and there provided with separately-removable lids or covers. The depressions or pockets in the bottom of the main itself form receptacles into which the tar falls from the dip-pipes, and prevent the tar 45 from spreading over the bottom of the main.

The invention also consists in making the bottom of the depressions or pockets and the back of the cleaning-holes or lateral branches curved or rounded in a direction transverse 50 to the main and straight in a direction lengthwise of the main, whereby the removal of tar

and other foreign matter by a hoe or like implement introduced through a hole or branch is facilitated.

The invention also consists in other novel 55 features in the construction of the main and its cleaning-holes, and in the manner of securing the covers of the cleaning-holes or branches, which are hereinafter particularly described, and pointed out in the claims. 60

In the accompanying drawings, Figure 1 is a front elevation of a bench of retorts and a hydraulic main embodying my invention. Fig. 2 is a sectional elevation on the dotted line *xx*, Fig. 1. Fig. 3 is a plan thereof. Fig. 4 is a 65 transverse vertical section of the improved main and a dip-pipe on a much larger scale. Fig. 5 is a side view on the same scale as Fig. 4, illustrating a short portion of the main, the cover of the cleaning-hole or branch being 70 removed; and Fig. 6 is a plan thereof, the dip-pipe and said cover both being removed.

Similar letters of reference designate corresponding parts in all the figures.

A designates the mouth-pieces of the retorts, five of which are here shown; and B designates the stand-pipes, which rise therefrom and are connected near their upper ends by bridge-pipes C with the dip-pipes D, as best shown in Fig. 2. This is a usual construction, and the upper ends of the stand-pipes B and dip-pipes D are closed by the usual stoppers, *b d*, which are luted with clay in the usual way. The lower portions, D', of the dip-pipes D are made separate from the 85 portions with which the bridge-pipes C connect, and are secured each by a flanged joint, *a*, to an upwardly-projecting branch, *a'*, formed on the hydraulic main E. The main E, which is of cast metal, is preferably of round or oval 90 transverse section, the major axis being vertical if the main is oval, and the flanges C at the ends of each section of the main rest in curved cradles C', which are supported by cast-iron saddles C", and are provided with 95 screws C", whereby the main may be leveled.

At the side of the main E are cleaning-holes or transverse branches E', and I prefer to provide such a cleaning-hole or branch opposite each dip-pipe D D'.

The construction of the main E with said cleaning-holes or branches E' and all other

features of the invention are best shown in the large views, Figs. 4, 5, and 6, to which I now particularly refer.

The dip-pipe D' extends downward below the liquid-level e to the desired extent, and there is in the main but a single gas-space, e' , unbroken by any partition, and to which there are no openings save the necessary gas-outlet. The flanges a , forming the joints between the necks or upwardly-extending branches a' and the dip-pipes D' , are faced, and when once packed and bolted together form permanent gas-tight joints. It will therefore be seen that there are no openings into the gas-space e' which are closed by covers or plates requiring to be often removed and replaced, as is the case where hand-holes are formed in the sides of a main above the liquid-level, and not only is the cost of construction of the main lessened, but the liability of any leakage of gas therefrom is greatly reduced. The mouth f of each cleaning-hole or branch E' is above the liquid-level e , and the opening f' , by which the cleaning-hole or branch communicates with the interior of the main, is entirely below the liquid-level, as shown in Fig. 4.

Directly below each dip-pipe D' is a depression, pocket, or sunken portion, g , in the bottom of the main, and the cleaning-hole or branch E' forms a transverse and rounded continuation of such depression or pocket, or a transverse and rounded continuation of the bottom of the main when no such depression or pocket is provided. The back g' of the cleaning-hole or branch, although curved outward and upward in a direction transverse to the main, is preferably flat or straight in a direction lengthwise of the main, as best shown in Figs. 5 and 6, and in the present example of my invention the transverse section of the cleaning-hole or branch is rectangular, as shown best in Fig. 6. The mouth f of the cleaning-hole or branch E' is presented upwardly on the exterior of the main, and is shown as inclined downward and outward from the side of the main. The cleaning-holes or lateral branches have no communication whatever with the gas-space of the main, and hence do not contain gas which will escape when the lids or covers are removed. It is closed by a cover, F , which, as shown, has a projection or lip, h , entering the mouth f , and extending around three sides thereof, thus preventing said cover from sliding downward and outward or laterally. In the under side of the cover F is a groove, i , which provides for luting the cover with clay to form a tight joint between it and the mouth f . The cover F is secured by a single bolt, j , which passes through a hole in the cover, and through a slotted lug or ear, K , projecting horizontally from the mouth f at the lower and outer side thereof.

At the upper side of the cover F is a lug or ear, l , which fits under a lug or ear, l' , cast on the side of the main. To remove the cover it

is only necessary to loosen the nut of the bolt j sufficiently to raise the lip h from the mouth f at the lower side thereof, and the cover may then be slipped off. To replace the cover the groove i is filled with clay, and the lug or ear l is slipped back under the lug or ear l' until the lip h will drop into the mouth f . The nut of the bolt j is then tightened to securely fasten the cover. When the cover F is removed, there can be no escape of gas, as the opening f' is below the liquid-level e , and consequently the making of gas need not to be interrupted. A hoe or other suitable implement is then introduced through the cleaning-hole or branch E' , and all matter deposited below the dip-pipe D' , whether it be clay, carbon, or either or both of these substances, with a deposit of hard tar, can be readily and completely withdrawn. The depression or pocket g and the making of the back g' of the branch E' straight in a direction lengthwise of the main and rounded in a direction transverse to the main greatly facilitate the withdrawal of the deposit. The depression g keeps the deposit from shifting lengthwise of the main when a hoe or implement is applied to it, and by the use of a hoe having a straight-edged blade of a width to drop into the depression g the deposit can be completely removed.

I am aware of patent to William Beal, granted August 16, 1881, and numbered 245,767, and do not claim anything therein shown or described as of my invention. In said patent there are no depressions or pockets in the bottom of the main; but at the side thereof are laterally-projecting casings, which communicate with the main below the liquid-level therein, and the mouths of which are above the liquid-level, and are provided with separately-removable lids or covers. In this patent the dip-pipes are not extended vertically downward into the main, but are vertical down to the main, and within the main are inclined at a sharp angle, to direct them toward the openings which communicate with the laterally-projecting casings. Such inclined pipes are not so desirable as my directly-vertical dip-pipes, because the tar and any wet clay falling from the luting of the stoppers at the top of the dip-pipes will be liable to lodge against the inclined back of the dip-pipes and soon form an obstacle which will clog them. Neither can such inclined dip-pipes be as readily cleaned as straight pipes, because the inclined portion cannot be reached by a cleaning-rod introduced from above.

What I claim as my invention, and desire to secure by Letters Patent, is—

1. A hydraulic main having a number of dip-pipes extending vertically downward into it, provided in its bottom with depressions or pockets directly below the downwardly-presented ends of the vertical dip-pipes, and having cleaning-holes or branches extending from

the depressions or pockets to the exterior of the main above the liquid-level, and there provided with separately-removable lids or covers, substantially as and for the purpose herein described.

5. A hydraulic main having at the side a cleaning-hole or branch, the mouth of which is presented at the exterior of the main above the liquid-level therein, and which communicates with the interior thereof below the liquid-level therein, the back of such cleaning-hole or branch being curved or rounded in a direction transverse to the main and approximately straight in a direction lengthwise of the main, substantially as and for the purpose herein described.

10. A hydraulic main having in the bottom and below the liquid-level a depression or pocket, and having a cleaning-hole or branch extending from such depression or pocket upward and outward to a point above the liquid-level in the main, the bottom of said depression or pocket and the back of said cleaning-hole or branch being curved or rounded 15 in a direction transverse to the main and straight in a direction lengthwise of the main, substantially as and for the purpose described.

4. The combination, with the hydraulic main E, having the cleaning-hole or transverse branch E', communicating with the interior thereof at f', and having its mouth f inclined downward and outward from the side of the main, of the cover F, provided with a lip, h, entering said mouth on the lower side or back thereof, substantially as and for the purpose herein described.

5. The combination, with the hydraulic main E, having the cleaning-hole or transverse branch E', communicating with the interior thereof at f', and the mouth of which is inclined downward and outward from the side of the main, and also having the lugs or ears l' and K, of the cover F, fitting under said lug or ear l' at its upper edge, and the bolt j, securing the cover at its lower edge, substantially as and for the purpose herein described.
